UNITED STATES PATENT OFFICE

1,957,195

CORNER CONSTRUCTION FOR TABLES

William Berssenbrugge, Milwaukee, Wis.

Application March 14, 1932, Serial No. 598,777

1 Claim. (Cl. 45—11)

The present invention relates to card tables or the like and has particularly to do with a corner construction for such tables.

Many card tables necessarily are of inexpensive construction. Tables of this type should be highly portable which necessitates that they be manufactured of light weight materials. In addition, such tables must be fairly strong. Apparently, a table having a permanent top with legs foldable within the area of the permanent top and in alignment with the rails for supporting the top is preferred over other varieties of tables.

The present invention has to do with a table of the character just described and the invention resides particularly in providing at the corners of such table suitable bracing means for insuring the rigidity of the top and concurrently arranging for the relatively firm support of the table legs. The legs illustrated are collapsible within the area defined by the reinforcing rails arranged beneath the table top.

Among the objects of the invention are the following:

25 A new and improved corner construction for a card table or the like.

An improved assembly of parts for use at the corner of the table and whereby firmness of structure as well as low cost production and assembly are assured.

30 An improved corner brace and leg support for a table.

New and novel means for constructing the corner of a table in which a collapsible leg is secured.

35 These objects, and such other objects as may hereinafter appear, are obtained by the novel construction, unique arrangement, and improved combination of the several elements which constitute the form of the invention illustrated in 40 the accompanying single sheet of drawing, hereby made a part of the specification and in which:

45 Figure 1 is a perspective view of the table embodying the subject matter of the present invention;

Figure 2 is a horizontal section on the line 2—2 of Figure 1 and illustrative of a corner of the table.

50 Figure 3 is a similar section at ninety degrees angle to the section in Figure 2 and is taken on the line 3—3 of Figure 2; and

Figure 4 is a bottom view of the table shown in Figure 1 with the legs retracted.

55 Like reference characters are used to designate similar parts in the drawing and in the description of the table which follows.

Reference should be had first to Figure 1. The top of the table illustrated comprises a rectangular sheet of material, generally fiber, which is indicated by the reference character 10. Surrounding said table top 10 are rails 11 which are in the form of wooden strips or the like, generally rectangular in transverse cross section. Rails 11 have beveled ends, as shown in Figure 2, and are suitably joined at their ends for the purpose of providing a satisfactory and right angle corner.

As shown in Figure 3, the fiber sheet 10 is secured to the corner piece by nails or tacks 12, the edges of the fiber resting on an undercut shoulder or longitudinal recess section 13. Between the shoulder 13 and the outer higher section 14 of each rail 11, there is a vertical slot 15 into which the edges of any covering material (not shown) which may be laid over the fiber sheet 10 (to provide a neat trim for the table) is adapted to be forced.

Each of the corners of the table is identical. The metal members comprising the corners are laid in rotation so that one leg only will be parallel and adjacent to each rail 11, as shown in Figure 4.

In each corner, there is a strap metal member which comprises a straight section 17 which has struck therefrom two tongues, 18 and 19. There is also disposed in said section 17 an aperture 20, the purpose of which will later be made apparent.

At a ninety degree angle to section 17 is a second section which comprises a portion 21, an offset portion 22 which has end sections 23 and 24, and a third section 25. In section 21 and 25 are tongues 26 and 27 which are struck from the material of the corner piece to project outwardly. There is in section 27 an aperture 28. By the arrangement described and illustrated, section 22 is offset from sections 21 and 27 by the oblique portions 23 and 24. In section 22 is an aperture 29.

A second metallic member, also angular in construction and of a strap material, is associated with the first referred to member. Said second member comprises an L-shaped construction shown in horizontal cross section in Figure 2 and having a short leg 31 and a longer leg 32. In the leg 31 is an elliptical aperture 33 and a similar aperture 34 is disposed in leg 32. The two strap metal parts, i. e., the two corner pieces are assembled as shown in Figure 2 with a table leg 36 between the off set section 22 and the leg 32.

For holding the larger member and the smaller

member in assembly at one end thereof, there is provided a rivet 36 which projects through the elongated slot of leg 31, through the aperture 20 in section 17, and through the wood member 11; 5 the head of the rivet preferably being at the outside of the table.

The other leg of the larger corner piece is attached to an adjoining rail 11 by running a rivet 37 through the aperture 28 therein and through 10 the wood section 11, there being supplied a washer 38 intermediate the spread end of the rivet 37 and the section 25. Intermediate the two members, and particularly between the apertures 29 in the offset section 22 and the aperture 34 in the leg 15 32, is a rivet 39. Preferably the head of the rivet 39 is disposed toward the rail 11 with the clinched head thereof falling within the offset space defined by the sections 23 and 24.

In such an assembly, the tongues 18 and 19, and 20 26 and 27, are forced into the material of the normally disposed table rails 11, the rivets 36 and 37 insuring a firm attachment of the larger corner piece. The rivet 36 of course insures firm jointure of the smaller angle piece to the larger corner member. By the use of elongated slots in 25 the smaller corner piece, the necessity for accurate assembly or accurate manufacture of the parts is avoided for the elliptical hole in the shorter leg permits of adjustment of the smaller L-shaped 30 member along the face of the larger member to accommodate legs 35 of different dimensions. Likewise, the elliptical hole 34 in the leg 32 increases the field of alignment therebetween and the aperture 29 in the off set portion 22.

35 Any standard brace comprising flat members 45 and 46 pivoted to form an elbow joint at 47 may be attached between a leg 35 and the adjacent side rail 11 to hold the leg in a position normal to the table top when the table is in use. The 40 end of the brace piece 45 is pivotally attached to the side member lying in parallelism to the folding plane of the adjacent leg while the extended end of the brace piece 46 is similarly attached to the opposed side of said leg. When the legs are 45 swung into the folded position the brace pieces 45 and 46 are brought into juxtaposition by extending the joint 47 toward the free ends of the legs and are disposed intermediate the respective legs and side members.

50 A table constructed in the manner indicated is strong. The metal parts are light. Said parts firmly hold a collapsible leg in position adja-

cent to the corner of the table and permit of ready folding beneath the table when collapse of the table is desired.

What is claimed as new and is desired to be secured by Letters Patent of the United States is:

In a table, a corner construction comprising side members with straight interior faces intersecting at a right angle, a pivoted leg, and side member reinforcing and leg supporting means, said means comprising two straps of metal each having legs at right angles to one another and each of width substantially equal to or greater than the major transverse dimensions of said leg, one of said straps having a leg with two spaced apart tongues penetrating the material of the adjacent side member and an aperture therethrough intermediate said tongues, the other leg of said side member having end portions disposed against the side member adjacent thereto and an intermediate part offset from said end portions, each of said end portions having a tongue penetrating said adjacent side member and one of said portions having an aperture therethrough, the offset part of said leg being of the full width of the leg and having an aperture therethrough, 100 said second strap member having two legs each with an aperture therethrough, the aperture in each leg being elongated longitudinally of the leg in which formed, and a plurality of fastening means, one of said fastening means extending through the second referred to leg of the first named strap member and through the adjacent side member, a second of said fastening means extending through the elongated aperture in one leg of said second referred to strap member, the aperture in the first referred to leg of the first referred to strap member, and the adjacent side member, and a third of said fastening means extending through the offset part in the second referred to leg of said first mentioned strap member, the table leg, and the elongated aperture in the second referred to leg in said second mentioned strap member, said third fastening means comprising a pivot for the table leg and the two elongated apertures in the legs of said second referred to strap member compensating for any irregularity in the position of the aperture in said offset part of the second referred to leg of said first referred to strap member and in the transverse dimension of said table leg.
